UNITED STATES PATENT OFFICE.

EDWIN S. FARRA, OF NEW YORK, N. Y., ASSIGNOR TO M. ACHFELDT, OF NEW YORK, N. Y., A CORPORATION OF NEW YORK.

FOOT APPLIANCE.

No. 892,412.

Specification of Letters Patent.

Patented July 7, 1908.

Application filed November 18, 1903, Serial No. 181,650. Renewed November 23, 1906. Serial No. 344,785.

To all whom it may concern:

Be it known that I, EDWIN S. FARRA, a citizen of the United States, residing at New York, in the county of New York and State of New York, have invented certain new and useful Improvements in Foot Appliances, of which the following is a specification.

My invention relates to foot appliances for use in the treatment of bunions, and its 10 primary object is to provide a simple and inexpensive but effective device adapted to be attached to the foot and so constructed and applied as to straighten the toe and thereby reduce the enlarged great toe joint.

15 A further object of the invention is to provide a device of the character named with means whereby it may be conveniently and adjustably secured to the foot, and around the toes.

20 The invention comprises a resilient splint or spring adapted for application to the inner side of the foot near the great toe, and having a cup or concave portion to receive the toe joint; a strap of leather or other pliable material adapted to be passed around 25 the foot over the instep to secure the splint in place; a strap adapted to encircle the great toe; and an independent strap adapted to be passed under the great toe and encircle one of 30 the other toes.

A distinguishing characteristic of the present improvement is that two independent straps or bands are provided for the treatment or separation of the great toe and second toe, each of said straps being attached at 35 one of its ends to the splint or spring, while its opposite or free end is adapted to be detachably secured to the splint or spring.

30 The construction of the device will be fully 40 described hereinafter in connection with the accompanying drawing which forms part of this specification, and its novel features will be defined in the appended claims.

45 In the drawing: Figure 1 is a side elevation of the device with its straps or bands disconnected and depending from the splint ready for application to the foot. Fig. 2 shows the device applied to a foot, the upper side or instep of the foot being shown, and 50 Fig. 3 represents the sole of the foot showing the adjustment of the straps.

55 The reference numeral 1 designates the metallic splint or spring enlarged at a point between its ends and hollowed out to form a cup, 2, having an elongated opening, 3, to

permit of the protrusion of the great toe joint, as clearly illustrated in Figs. 2 and 3. The splint or spring, 1, is provided with a suitable lining, 4, of felt or like yielding material. To the rear end of the spring, 1, is riveted a strap, 5, of leather or other pliable material, both ends of said strap preferably projecting beyond the spring. The short end, 6, of the strap, 5, is provided with one member of a catch, preferably a resilient head, 7, while the opposite end of the strap is provided with a plurality of sockets, 8, thus providing for the adjustability or loosening or tightening of the strap. This strap, 5, is adapted to be passed around the foot, as 70 shown in Figs. 2 and 3.

To the forward end of the spring is riveted one end of a strap, 9, the free end of which is provided with a plurality of sockets adapted to receive the resilient head, 10, projecting 75 from the strap between its securing rivets. This strap, 9, is adapted to be passed around the great toe, forming a loop which securely holds the front end of the spring in position.

11 designates a supplemental strap of less 80 width than the strap, 9, and riveted to the spring, 1, in rear of said strap, 9.

In Figs. 2 and 3 the strap, 11, is shown as first passing under the great toe, then encircling the second toe and then again passing 85 under the great toe, after which it is secured by its fastenings.

An important advantage of the improvement is that the straps for both toes are secured directly to the spring, and all of the 90 three straps are so secured to the spring as to be in parallel relation.

The utility of the adjustable fastenings of the straps will be apparent and the pliable nature of the straps insures comfort to the 95 wearer.

I would have it understood that the invention comprehends all such minor changes in the details of construction as may properly fall within the scope of the following claims. 100

I claim:

1. A foot appliance comprising a resilient metallic splint provided with a concave perforated portion, a strap secured to the rear end of said splint and two straps of different 105 widths secured to the forward portion of the splint, one of the latter straps adapted to encircle the great toe, and the other adapted to encircle one of the other toes, all of said straps having a plurality of fastening devices 110

to permit of the loosening or the fastening thereof.

2. A foot appliance comprising a resilient metallic splint provided with a concave perforated portion, a strap secured to the rear end of said splint and two straps of different widths secured to the forward portion of the splint, one of the latter straps adapted to pass below the great toe and the other adapted to pass below the great toe and encircle the second toe.

3. A foot appliance comprising a resilient metallic splint having a cup or concavity at a point between its ends; a yielding lining

for said splint, a strap at the rear end of the 15 splint adapted to pass over the instep; a strap secured at one end to the forward end of the splint to encircle the great toe; and a third strap of less width than the great toe strap secured at one end to the splint and 20 adapted to pass over the great and second toes.

In testimony whereof I affix my signature in presence of two witnesses.

EDWIN S. FARRA.
